UNITED STATES PATENT OFFICE

AUGUSTO E. MUELLER, OF CHICAGO, ILLINOIS, ASSIGNOR OF ONE-HALF TO MAURICE BRITZ, OF CHICAGO, ILLINOIS

BRUSH-MAKING MACHINE

Application filed November 3, 1924. Serial No. 747,483.

The invention herein disclosed pertains to the manufacture of brooms, brushes, mops and the like and is more particularly directed to a machine for manufacturing articles of this class such as those set forth in my copending application, Serial No. 747,484, filed of even date herewith.

In the manufacture of brooms, brushes, mops, swabs, and the like, it has been usual to bind the bristles, fiber, or other material of which the article may be composed, into a more or less loose bundle, and to back the bundle or otherwise provide it with a handle for use. This binding is generally done by hand, though machines for sewing wire or thread through and through the fiber to secure it in an aggregate bundle are sometimes provided, but do not thoroughly secure the material together, since they are not constructed to do more than quicken the operations heretofore performed by hand. In no case, however, to my knowledge, has a machine been provided which will compress the fiber of the broom, brush, mop or the like, to a substantial solid condition and simultaneously bind the material permanently in that relation.

With the aid of my invention the old methods of manufacturing brooms, brushes, and the like may be antiquated, for with its use, I am enabled to provide an article at a minimum price without decreasing durability. The machine which I have constructed embodying this invention is of itself novel in its functional ability to carry out parts of the process disclosed in my aforesaid copending application. The process disclosed in this copending application consists, briefly stated, in cutting the material of which the article is to be made into lengths slightly greater than necessary or desirable for the finished article to allow for trimming, positioning a predetermined amount of this material within a suitable clamp or securing means, compressing the material adjacent

one end of the aggregate until substantially no interstices remain between them or until the pressure causes the individual fibers to frictionally interengage one another to prevent their being pulled out under normal and continued usage, and tightly securing the clamp or other securing means about the ends of the fibers while they are thus held under compression. Further description of the process is unnecessary, although it may be had upon reference to said copending application.

Throughout the description and claims I shall refer to the material of which the body or working portion of the broom, brush, mop, or the like is composed as "fiber", regardless of whether or not this material be true fiber, such as that of jute, hemp, or corn, for it is obvious that wire, cord, rags, or any other material or form thereof, serviceable for use as a broom, mop, or swab, may be used in its stead. Under these circumstances, it should be clearly understood that the term "fiber" is used herein without desire to limit the scope of the claims to "fiber" in its strict definition. Other materials are intended to be included within the term and come within the spirit of my invention.

One object of my invention is to provide a machine for automatically "setting" the fibers or their equivalent for the manufacture of brooms, brushes and the like, tightly together. In this connection, I prefer to use what I may term a clamp member and I set the fiber so securely therein that it will resist all reasonable efforts to remove it longitudinally.

Another object is to provide a machine which will receive and press the fibers of the article into such compact relation that the size or number of the interstices between the individual fibers at the point of binding or compression will be reduced to a substantial minimum.

Still another object is to provide a machine

which will exert pressure upon a bundle of fiber sufficient to tightly compact it and which, while so pressing the fiber will engage a clamp or other securing means about the fiber at or about the point or points in compressed condition.

Further objects will appear and should be appreciated from the following description and claims taken in connection with the drawings in which:

10 Fig. 1 is a front elevation of a portion of a machine embodying my invention;

Fig. 2 is a similar view to that of Fig. 1, parts being taken in section;

15 Fig. 3 is a view taken substantially along the line 3—3 of Fig. 2;

Figs. 4 and 5 are views similar to that of Fig. 2 but with parts broken away and showing consecutive steps of the machine's operation;

20 Fig. 6 is a section taken along the line 6—6 of Fig. 5, and,

Fig. 7 is a view of a preferred form of fiber clamp.

25 In illustrating my invention, I have not shown a complete machine, but only a die member operatively engaging with the head of an ordinary punch press or the like, but it should be understood that a complete machine embracing my invention integrally within its component parts may be constructed and utilized for my purpose. Mounted between a bed 2, which is preferably vertically adjustable, and a reciprocable head 4 of a 30 punch press, is a die mechanism generally designated 6 and composed of a bed member 8 carrying a pair of U-shaped guide blocks 10, a center block 12 recessed at 14 and 16 to receive springs 18, which are respectively 35 connected at their outer ends to horizontally reciprocable die members 20, a work receiving bed or supporting plate 22 and a recessed position or guide block 24. The block 24 may be adjustably secured with respect to 40 the block 12 by means of screws 25, and while the blocks 12, 22, and 24 may be formed integral with the bed 8 of the lower die members they are preferably removably secured 45 in position thereon and are made in different 50 interchangeable sizes. The blocks 10 are preferably arranged for adjustment toward and from one another and for this purpose are slotted as shown at 13 and are secured in adjusted position by means of bolts 15.

55 These parts described partake of no vertical movement generally except that the bed plate 2 may be raised or lowered with respect to the head 4, as is common in punch presses and the like, for adjustment relative to the 60 opposing die members.

On the other hand the punch press head 4 is reciprocable and usually recessed to receive a shank 26 or any other suitable connection between it and the vertically movable die members cooperative with those fixed

upon the bed plate 2. In this instance, the shank 26 is formed integral with a head 28 adapted to receive a punch die, or the like, 30 removably secured therein by means of a set screw 32 and carries a resiliently mounted 70 plate or secondary head 34 through which the punch 30 passes, to which head 34 is secured in any suitable manner such as by stud bolts 36, a pair of spaced presser feet 38 and 40. The head 34, with its presser feet is reciprocably mounted in the head 28, which is recessed as at 42 (one recess shown) to receive the heads of stud bolts 44 and 46 slidably therein. These bolts may be adjusted to vary the distance between the heads 28 and 34, and so locked in adjusted position by means of lock nuts 48. Springs 50 and 52 are interposed between the heads 28 and 34 in any suitable manner to normally urge and hold these members in spaced relation while movement of 85 the head 34 toward the head 28 is limited by engagement of the heads of the stud bolts 44 and 46 with the bottom face of the punch press head.

Secured to opposite sides of the head 28 by means of stud bolts 54 and with shims or washers 55 interposed, is a pair of similar cam arms 56 provided with bevelled faces 58 adapted to engage with correspondingly bevelled ends of the horizontally reciprocable 95 die members so that when the head 28 is moved downwardly, the cam surfaces will engage the ends of the dies 20 to move them inwardly toward one another. The plate 8 is suitably recessed at 59 to permit downward passage of 100 the cam arms 56 and are slightly wider, in one direction, i. e., in a direction toward one another, than in the other for a purpose to be explained.

The positioning block 24 is recessed as at 105 60 to a width suitable to receive a bundle of fiber 62 which may be held within a receptacle 64, more particularly described in my copending application, and the block 12 is correspondingly recessed as shown at 66 to 110 confine and position the ends of the fiber with respect to the pressing and clamp setting dies. The horizontal dies 20 travel in slots 67 in the block 12 and are proportioned and arranged to fall short of being flush with the 115 sides of the recess in the positioning block 24 while the guide block 12 is slightly recessed as at 68, in order that a U-shaped clamp 70 may be set and substantially fixedly positioned therein. Thus, when the ends of the 120 fiber contained in the receptacle 64 are placed between the clamp dies, they will fall within the vertical sides of the clamp 70.

In operation, a bundle of fiber, inclosed within its receptacle or held within the hand 125 of the operator so that the ends thereof will project a reasonable distance beyond, is placed upon the supporting plate 22 with the ends within and abutting against the back of the recess 66 and within the sides of the 130

clamp 70 which has previously been set within its positioning recess. In this position, the fiber is confined horizontally or transversely of its length while the head 4 is brought down until the presser feet 38 and 40 resiliently engage the top of the bundle of fiber on both sides of the clamp 70 as shown more clearly in Figure 6.

This movement of the head 28 downward continues, resiliently compressing the fibers until the heads of the guide bolts 44 abut the face of the die press 4, which continues downward further compressing and holding the fiber in tightly compressed relation while the cam arms 56 through their bevelled faces 58 force the horizontally reciprocable dies 20 toward one another and into engagement with the vertical sides of the clamp 70 to force them inwardly to a point shown in Figure 4.

At this point, continued downward movement of the head 28 has brought the punch 30 down to a point where it will engage the bevelled ends of the clamp to force them down into overlapping engagement and into contact with the fiber to securely clamp it in compressed relation, as shown in Figures 5 and 6. This last operation being completed, the head 4, carrying the upper die members 30 is retracted to permit removal of the clamped fiber which is then finished in accordance with the disclosure in my copending application. Retraction of the head permits the springs 18 to move the dies 20 apart.

The clamping member 70 is preferably made of annealed spring steel although any other material capable of being distorted and retaining its distorted form to tightly and substantially permanently hold the fiber in compact and compressed relation may be used. As it is essential for some kinds of fiber or material of which the body of the brush is composed, that it be held in tightly compressed relation during the clamp securing operations, it will be appreciated that my machine performs unique functions.

Long continued use of the machine may cause the horizontal clamp distorting dies 20 and their associated mechanism to wear to a greater or less degree and it becomes necessary to take up this wear or to replace the worn parts. In the embodiment illustrated, wear may be compensated by removal of one or more shims 55 and by inward adjustment 50 of the blocks 10. The slots 59 are accordingly made wide enough to permit such adjustments. It may be desired to vary the amount of fiber to be bundled or clamped and to this end, the parts of the machine may be made 55 in various sizes and adjustment of the relation of the upper and lower die members and their operating mechanism may be made accordingly.

While a preferred form of my invention 60 has been illustrated and described, many

modifications may be made as will be appreciated by one skilled in the art and I do not, therefore, desire to be limited except by the spirit of my invention and the scope of the appended claims.

I claim:

1. A machine of the class described comprising, means to laterally confine a plurality of fibers within a predetermined area and for a predetermined fiber length, means cooperative with said confining means to compact said fibers at spaced places, and means independent of said cooperative means operative to apply a fastener about said fibers between said spaced places to hold them in compacted relation.

2. A machine of the class described comprising, means to laterally confine a plurality of fibers within a predetermined area and for a predetermined fiber length, resiliently mounted means cooperative with said confining means to compact said fibers, and means operative upon completion of the compacting operation to secure said fibers in compacted condition.

3. In a machine of the class described, a die to receive and position a bundle of fiber and constructed and arranged to position a U-shaped clamping member in proximity to and adjacent one end of said bundle, means for compressing the fiber on opposite sides of said member opposed means simultaneously operative to engage opposite sides of said U-shaped member to preliminarily distort them, and means operative thereafter to drive said sides into clamping engagement with said bundle.

4. A machine of the character described comprising, means for confining the sides of an end of a bundle of fiber, means for supporting spaced portions of the bottom of the bundle at said end, means for engaging the top of said bundle at spaced places in register with said supporting means for compressing said fiber, means for supporting an open staple about a portion of said bundle between said spaced places and means including laterally movable dies for applying and securing the staple about said bundle between said places of its compression.

5. A machine of the character described comprising, means for confining the sides of an end of a bundle of fiber, means for supporting spaced portions of the bottom of the bundle at said end, reciprocable means for engaging the top of said bundle at spaced places in register with said supporting means for compressing said fiber thereat, means for supporting a U-shaped band about a portion of said bundle between said spaced portions, and means including laterally movable dies and a vertically movable die independent of said reciprocable means for securing the band about said bundle between said places of compression.

6. In a machine of the class described, a
die for receiving and positioning a bundle of
fiber and having a recess for holding and
positioning a **U**-shaped clamping member
adjacent one end of said fiber with the bot-
5 tom of the **U** transverse said fiber, die means
for compacting said end of said bundle at
spaced places on opposite sides of said mem-
ber, transversely movable means for pre-
liminary distorting the sides of said member
10 over said end of said bundle of fiber, and
means thereafter operative for forcing the
ends of said member into clamping engage-
ment with the fiber about said bundle end.

AUGUSTO E. MUELLER.
